UNITED STATES PATENT OFFICE.

EDWIN I. HEINSOHN, OF LAKewood, OHIO.

RECEPTACLE.

Application filed October 13, 1922. Serial No. 594,400.

To all whom it may concern:

Be it known that I, EDWIN I. HEINSOHN, a citizen of the United States, residing at Lakewood, in the county of Cuyahoga and 5 State of Ohio, have invented a certain new and useful Improvement in Receptacles, of which the following is a full, clear, and exact description, reference being had to the accompanying drawings.

10 This invention relates to receptacles and is directed more particularly to that class of receptacles which are commonly known as carboys.

Some of the objects of the present invention are to provide a carboy which shall be made from sheet metal suitably reinforced and provided with a coating which shall resist the action of acids or other chemicals which it is adapted to contain; to provide a 20 carboy which shall effectively resist rough handling that would ordinarily damage the glass carboys in present use; to provide a carbody which shall be simple in construction, inexpensive to manufacture, and which 25 shall not be subject to leakage.

In the accompanying drawing wherein I have shown one form of my invention, Fig. 1 is a vertical sectional view through a carboy constructed in accordance with my invention; Fig. 2 is a transverse sectional view taken on the line 2—2 of Fig. 1; and Fig. 3 is a detail sectional view showing a modified manner of attaching the cover to the body portion of the carboy.

30 Describing by reference characters the various parts illustrated, 1 denotes the body portion of the carboy which in the present instance is cylindrical in shape and pressed from sheet metal. The upper peripheral edge is rolled outwardly and downwardly as indicated at 2, and a bead 3 extends circumferentially about the side walls of the body portion. A plurality of wooden staves 5 enclose the outer side walls 4 and a pair of 40 metal bands 6 and 7 arranged in spaced relationship retain the staves in position. As shown in Fig. 1, these staves preferably extend below the bottom 8 so as to form a support for the carboy and also to protect the 45 bottom 8 from severe shocks and dents. An internal metal band 9 is applied to the inner surface of the staves about the portion thereof which extends below the bottom 8, and this band prevents the staves from splintering 50 during the handling of the carboy. Suitable handles 10 may be fastened to the band

6 at diametrically opposite points to facilitate handling of the carboy.

The top of the body portion 1 is closed by a sheet metal cover 12 which is provided with a spout 13 located adjacent the circumferential edge thereof. As shown in Fig. 1 the peripheral edge of this cover is directed downwardly and inwardly as indicated at 14 and is of such diameter as to overlap the 60 rolled edge 2 of the body portion. In applying this cover to the body portion, I first place a ring 15, of heat resistant material such as asbestos, about the top edge of the body portion and then apply the cover thereto. The carboy is then inverted and molten lead 16 or other suitable material is poured into the space between the wall of the body portion and the edge 14 of the cover. In this manner the cover is securely held to the 70 body portion and a nonleakable joint formed therebetween. The edge 14 preferably extends slightly below the sealing material 16 so that the upper ends of the staves 5 may be notched and fitted therein as shown in 75 Fig. 1.

In order to protect the metal parts of the carboy which are exposed to the action of the chemicals contained therein, I apply a 80 vitreous coating 18 such as glass, to the inner surface of the body portion 1 and also to the entire inner and outer surfaces of the cover 12. In this manner I protect the metal portion of the carboy from the chemicals contained therein and also from any chemicals which may be spilled on the cover 12 85 during filling and emptying of the carboy.

In Fig. 3 I have shown a modified manner of fastening the cover 12^a to the rolled edge 2 of the body portion. In this instance 90 I provide the downwardly directed peripheral edge 20 with an inwardly directed bead 21. A ring 15^a of heat resistant material is interposed between the cover and rolled edge 2 and the intervening space between the body portion and edge 20 is filled with molten lead 22. The lead is preferably filled to the shoulder 23 defined by bead 21 so as to 95 form a flat abutting surface for the upper notched ends of the staves 24. The remaining structure is substantially the same as 100 previously described.

Having thus described my invention, what I claim is:

1. A carboy for acids and other chemicals 110 comprising a sheet metal vessel having side and bottom walls and open at the top, the

upper peripheral edge of said side walls being directed outwardly and downwardly, a sheet metal cover applied to the top of said vessel and having the peripheral edge thereof directed downwardly and inwardly and overlapping but spaced from the peripheral edge of said vessel, the space between said cover and the walls of said vessel being filled with molten lead, means for protecting the metallic surfaces of said carboy from the chemical action of the contents thereof, and a wooden casing enclosing the side walls of said carboy and extending below the bottom thereof.

15. 2. A carboy for acids and other chemicals comprising a metallic vessel having side and bottom walls and open at the top, a reinforcing bead extending circumferentially about the side walls of said vessel, a cover

fitted to the top of said vessel and having a 20 downwardly directed peripheral edge portion spaced from the side walls of said vessel, sealing means disposed within the space defined by said edge portion and side walls, a vitreous coating applied to the inner surfaces of said vessel and cover, and a wooden casing consisting of a plurality of vertically disposed staves enclosing the side walls of said vessel, the upper ends of said staves being inserted within the space defined by 25 the edge portion of the cover and side walls of said vessel, and the lower ends of said staves extending below the bottom of said vessel.

In testimony whereof, I hereunto affix my 30 signature.

EDWIN I. HEINSOHN.
